UNITED STATES PATENT OFFICE.

WEBSTER C. ESTES, OF NEW YORK, N. Y.

DESIGN FOR A TURNED WOODEN BOX.

SPECIFICATION forming part of Design No. 31,997, dated December 19, 1899.

Application filed November 21, 1899. Serial No. 737,823. Term of patent 14 years.

To all whom it may concern:

Be it known that I, WEBSTER C. ESTES, a citizen of the United States, residing at New York, (Brooklyn,) in the county of Kings and State of New York, have invented and produced a new and original Design for a Turned Wooden Box, of which the following is a specification, reference being had to the accompanying drawings, in which—

10 Figure 1 is an elevation, Fig. 2 an end view, and Fig. 3 a longitudinal section.

The general configuration of my new design for a turned wooden pencil-box or scholar's companion is round; and the leading features 15 of my design consist in the cylindrical configuration with flat ends, plain parallel sides, and series of adjoining alternate annular beads and ribs at the respective ends and about the center of the box.

20 The design of the body portion of the box comprises the parallel sides *a*, the series *b* of

adjoining alternate annular beads *2* and ribs *3*, adjacent to the flat end *c*, and the similar smaller series *d* of adjoining alternate annular beads *2* and ribs *3*, adjacent to the reduced open end *e* of the box. 25

The design of the removable end comprises the plain parallel sides *a'* and the series *f* of adjoining alternate annular beads *2* and ribs *3* at the flat end *g* of the box. The series *b* 30 and the series *f* preferably agree in the number of the beads and ribs.

What I claim is—

The design for a turned wooden box, substantially as shown and described.

Signed by me this 18th day of November, 1899. 35

WEBSTER C. ESTES.
